WIRE BUNDLING MECHANISM

Norman H. Nye, Cuyahoga Falls, Ohio, assignor
to The Vaughn Machinery Company, Cuyahoga
Falls, Ohio, a corporation of Ohio

Application January 7, 1948, Serial No. 851

8 Claims. (Cl. 242—78)

1

The present invention, while relating generally as indicated to a wire bundling mechanism, is more especially concerned with certain improvements by which automatic control of such mechanism is achieved.

Wire bundling mechanism as known in the wire drawing art usually comprises a vertically disposed rotary draw block having the primary function of drawing wire through a die adjacent thereto and the secondary function of forming the drawn wire into a coiled bundle thereabout, said block being provided with vertical extension pins or the like for guiding the upward growth of the bundle. Without more, the operation of such a mechanism entails a certain amount of danger to the operator in the event that the bundle formed thereby is allowed to grow to an extent such that the ring generally employed about said pins and engaged with the top of the growing bundle is lifted above the upper ends of said pins and thrown off. In addition, overflow of the bundle above said pins may cause snarling or tangling of the wire, thus necessitating shutting down of the mechanism with a consequent loss of production and entailing added expense for loss of the tangled material or for labor expended to untangle the same.

As a safeguard against the aforesaid occurrences it is known to employ mechanical devices on the draw bench in the form of lever assemblies or the like engaged by said ring and operative upon being raised to a predetermined height by the upward growing of the bundle to actuate a switch controlling the block driving motor and thus interrupt operation of said block. However, after such device has so operated, the same must be moved to a position clearing the block so that the completed bundle may be lifted over the block extension pins and thereafter must be re-positioned over the block to re-initiate operation of the block and to engage the next succeeding bundle to be formed thereby.

Accordingly, it is one primary object of this invention to provide an automatically controlled wire bundling mechanism which does not require the aforesaid manipulations by the operator thereof.

Another object is to provide a wire bundling mechanism so formed that there are not mechanical connections between the power-operated block and the automatic control means therefor.

Other objects and advantages will become apparent as the following description proceeds.

To the accomplishment of the foregoing and related ends, said invention, then, comprises

the features hereinafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 is a front elevation view of a preferred embodiment of the present invention;

Fig. 2 is a top plan view of the mechanism illustrated in Fig. 1;

Fig. 3 is an enlarged cross section view taken substantially along line 3—3, Fig. 1;

Fig. 4 is an enlarged cross section view taken substantially along line 4—4, Fig. 1; and

Fig. 5 is a schematic wiring diagram of a typical control circuit for the motor which drives the draw block.

Referring now to the drawing and first more especially to Figs. 1 and 2, there is shown therein a portion of a draw bench 1 on which is mounted for rotation about its vertical axis a draw block 2 of conventional construction, said block being rotated as by any suitable electric motor and gear unit 3 having a spindle 4 keyed to said block. Said block preferably comprises tapered flange and frusto-conical portions 5 and 6 joined together by a fillet portion 7, all of such portions being smoothly finished so that wire wrapped thereabout for drawing and accumulated thereabout during the drawing operation will be caused to progressively slide upward along said block. As a safety feature a guard ring 8 mounted on said draw bench surrounds the lower flange portion 5 of said block.

Projecting upwardly from said block are a plurality of circularly arranged block extension pins 9 which serve to retain the accumulated wire (represented by dotted line 13 in Fig. 1) above said block as the bundle grows and is forced upwardly during the drawing operation. Around said pins is a ring 10 which is engaged by the top of the growing bundle and thereby progressively forced upwardly with the bundle.

From the structure thus far described it is apparent that should the operator be absent or inattentive, the combined drawing and bundling operation is apt to be continued until the bundle 13 and said ring 10 overflow above the upper ends of said pins 9, thereby involving the dangers and inconveniences previously referred to. In order to prevent such happenings and the resulting confusion and possible injury to the operator there is provided a light sensitive or so-called

"electric eye" assembly with the light source and light sensitive target elements thereof respectively carried by standards 11 and 12 on said draw bench, said standards being mounted in spaced-apart relation adjacent said block so that the light beam (dot-dash line 14 in Fig. 2) between said elements is tangent to a circle circumscribing said pins, such circle, of course, being of diameter less than that of ring 10 or the coiled bundle 13 of wire formed around said pins. As will be presently explained, the light source and target elements are vertically adjustable along said standards and are so coupled with the block driving unit that when the bundle 13 attains a predetermined size as determined by its height along said pins 9, said ring 10, or alternatively if no ring 10 is employed, the top of the bundle will interrupt the light beam 14 and thereby effectuate through a suitable means interruption in the further operation of said driving unit 3.

In Fig. 5 the exemplary "electric eye" assembly circuit includes a light source element 15 directing its light beam 14 at the light sensitive target element 16 (herein a photo-tube or photo-electric cell), which target element is operable when exposed to the beam 14 to release or emit photo electrons and thus establish flow of photo-electric current in the lines 17 and 18 under the influence of electro-motive force across said lines. On the other hand when the beam 14 is interrupted as by said ring 10 as aforesaid such emission of photo electrons ceases and therefore the flow of current through lines 17 and 18 likewise ceases.

Connected in series with said target element 16 is a relay 19 having an armature 20 movable in a direction to close the circuit through the power lines 21 and 23 to the block driving motor 3 in response to the energization of solenoid 25 by current flowing in the lines 17 and 18. Said armature is moved in an opposite direction to open the motor circuit by means of a spring 26 whenever said solenoid 25 is de-energized as when the light beam 14 is interrupted as aforesaid. Said motor circuit preferably has a main switch 27 therein to enable stopping of said motor 3 whenever desired. It is to be understood that this circuit and the components therein are merely typical and that in addition thereto it may be necessary or desirable to employ the usual thermionic amplifiers to step up the photo electric current to a value sufficient to actuate said relay 19. Likewise, although the illustrative circuit in Fig. 5 utilizes a target element 16 of the photoemissive type which is operative to interrupt flow of current when the light striking its cathode is cut off, it may be feasible in some cases to utilize other types of elements, viz. photo-conductive and photo-voltaic cells in which a change in resistance and voltage respectively is effected whenever light strikes the same. It is further contemplated that the circuit might be so modified that said motor 3 is rendered inoperative when the light beam 14 strikes the target element. In such modification, the ring 10 must, of course, be formed so as to traverse such light beam during the growth of the bundle and upon movement of said ring to a predetermined position to permit such light beam to strike the target element.

Said standard 11 is preferably of a curved form, as shown, with its upper horizontal leg portion disposed above said block and tangent

to a circle of diameter greater than said block 2 so as to properly clear the latter and other parts (not shown) on said draw bench 1. As best shown in Fig. 4, the upper end of said standard 11 has a vertically disposed cylindri-form housing 28 secured thereto, said housing being formed with two diametrically opposed and vertically extending slots 29 and 30. Vertically adjustable in said housing is a light-source holder 31 (light source element 15 omitted in Fig. 4) comprising a rectangular member having a lens 32 secured to one side thereof as by a nut 33 with said lens in register with slot 30 in said housing and having a stud 34 projecting from its opposite side through slot 29. Said holder is locked in any vertical position along slot 29 as by means of a nut 35 threaded on said stud and operative to draw the cylindrical sides 36 of said holder and a washer 37 on said stud toward one another with said housing clamped therebetween. Because the sides 36 are of diameter substantially equal to the inside diameter of said housing and because said stud has a clearance with slot 29, said holder may be angularly adjusted so that the beam of light 14 passing through the lens 32 and slot 30 may be accurately aimed at the target 16 carried in standard 12. The light source 15 will be mounted in the area 38 within said holder 31 in a conventional socket (not shown) and the leads 39 thereof as shown in Figs. 2 and 5 will extend through opening 40 in housing 28 into standard 11 and will emerge from said standard as through a lateral opening near its base for connection to a convenient electrical outlet.

Fig. 3 is a cross section view of the upper end of said standard 12 and, as shown, said standard 12 is formed with two diametrically opposed vertically extending slots 41 and 42 therethrough which correspond respectively with slots 29 and 30 in the housing 28 on standard 11, such slot 42 facing toward slot 30 and such slot 41 having projected therethrough the stud portion 34 on the target holder 43 disposed within said standard 12. Said target holder 43 is vertically adjustable in said standard 12 and lockable in a pre-selected position in line with the light beam 14 by a nut 35 and a washer 37 on said stud in the same manner as the light source holder 31 is adjusted and locked in housing 28. Said holder 43 is formed with a contractible device 45 which is operative to clamp the previously described target 16 (not shown in Fig. 3) therein whereby its photo-electron emissive cathode is exposed to the light beam 14 from said light source 15 which is carried in said standard 11. The lines 17 and 18 connected to said target pass through standard 12 and emerge through a side wall opening near its base for connection with a battery or other source of electro-motive force and a relay or the like as previously indicated with reference to Fig. 5.

With the light source element 15 and target element 16 properly adjusted in standards 11 and 12 so that the light beam 14 between said elements is at a desired height relative to the block extension pins 9 and with the main switch 27 closed, said draw block 2 will be driven by motor 3 so long as the ring 10 around said pins 9 is below the light beam 14. As the bundle of wire grows upward on said block and pins, said ring 10 will be correspondingly forced upward until it finally reaches the adjusted level of the light source and target elements 15 and 16. At this point the light beam 14 will be interrupted to thereby cut off the light to the target 16 whereby

relay 19 will be operative to open the block driving motor circuit to thus stop further rotation of said draw block. Such stopping of the block occurs before said ring 18 and the coiled bundle engaged thereby overflows over the upper ends of the block extension pins 9. The completed bundle of proper size can then be removed and in so doing, the mechanism is automatically conditioned for re-initiation of the operation of said block, the light beam 14 again shining on target element 16 for closing the block driving motor circuit.

With the improved mechanism disclosed herein it is unnecessary for the operator to manipulate any mechanical stop devices, viz. move such devices to clear the completed bundle to permit lifting of the bundle over the block extension pins and re-position such devices over said block in order to initiate another drawing and bundling operation. Furthermore, the present mechanism is safe and convenient with regard to precluding injury to the operator and tangling or snarling of the wire by overgrowth of the bundle.

Although but one form of draw block is herein disclosed, other forms may be equally well suited to the accomplishment of the distinctive features of this invention. For example, it is known to provide a flanged drum telescopically fitted within the draw block, said drum being raised by the growing bundle engaged with the flange thereof. Thus it is apparent that an "electric eye" assembly may be associated with such drum for interrupting operation of said block whenever the drum is raised to a predetermined height by the growing bundle.

Other modes of applying the principle of the invention may be employed, change being made as regards the details described, provided the features stated in any of the following claims, or the equivalent of such, be employed.

I therefore particularly point out and distinctly claim as my invention:

1. In wire bundling mechanism, the combination with a vertically disposed draw block operative when rotated to draw wire thereonto and form such wire into a coiled bundle which moves upwardly along said block as it grows, of driving means for said block, spaced apart standards respectively carrying light source and light sensitive target elements with a light beam from the former element shining on the latter element and lying on a line tangent to a circle about said block and above such bundle, said driving means and target element being so connected together that the former is rendered operative and inoperative in response to such light beam shining on and being cut off from the latter respectively, and means on said block operative upon predetermined upward movement of such bundle to cut off such light beam from said target element, one of said standards having a vertical lower portion and a horizontal upper portion extending generally toward said block and away from the other standard and carrying one of said elements at its free end.

2. In a wire bundling mechanism, the combination with a vertically disposed draw block operative when rotated to draw wire thereonto and form such wire into a coiled bundle which moves upwardly along said block as it grows, of driving means for said block, spaced apart standards respectively carrying light source and light sensitive target elements with a light beam from the former element shining on the latter element and lying on a line tangent to a circle about said

block and above such bundle, said driving means and target element being so connected together that the former is rendered operative and inoperative in response to such light beam shining on and being cut off from the latter respectively, means on said block operative upon predetermined upward movement of such bundle to cut off such light beam from said target element, holders for said elements within said standards, said standards each being formed with diametrically opposed vertically extending slots one of which provides a window for such light beam and the other of which provides for vertical adjustment of said holders in said standards, and means for clamping said holders in vertically adjusted position on said standards comprising a stud on each holder projecting through such other slot and a nut threaded on said stud.

3. In wire bundling mechanism, the combination with a vertically disposed draw block operative when rotated to draw wire thereonto and form such wire into a coiled bundle which moves upwardly along said block as it grows, of driving means for said block, spaced apart standards respectively carrying light source and light sensitive target elements with a light beam from the former element shining on the latter element and lying on a line tangent to a circle about said block and above such bundle, said driving means and target element being so connected together that the former is rendered operative and inoperative in response to such light beam shining on and being cut off from the latter respectively, means on said block operative upon predetermined upward movement of such bundle to cut off such light beam from said target element, holders for said elements within said standards, said standards each being formed with diametrically opposed vertically extending slots one of which provides a window for such light beam and the other of which provides for vertical adjustment of said holders in said standards, and means for clamping said holders in vertically adjusted position on said standards comprising a stud on each holder projecting through such other slot and a nut threaded on said stud.

4. In wire bundling mechanism, the combination with a vertically disposed draw block operative when rotated to draw wire thereonto and form such wire into a coiled bundle which moves upwardly along said block as it grows, of driving means for said block, spaced apart standards respectively carrying light source and light sensitive target elements with a light beam from the former element shining on the latter element and lying on a line tangent to a circle about said block and above such bundle, said driving means and target element being so connected together that the former is rendered operative and inoperative in response to such light beam shining on and being cut off from the latter respectively, means on said block operative upon predetermined upward movement of such bundle to cut off such light beam from said target element, holders for said elements within said standards, said standards each being formed with diametrically opposed vertically extending slots one of which provides a window for such light beam and the other of which provides for vertical adjustment of said holders in said standards, and means for clamping said holders in vertically adjusted position on said standards comprising a stud on

each holder projecting through such other slot and a nut threaded on said stud, at least one of said studs having clearance with such other slot whereby the associated holder may be angularly adjusted in a horizontal plane, said last-named holder and the standard in which it is disposed being formed with complementary inter-engaged cylindrical surfaces.

5. In wire bundling mechanism, the combination with a vertically disposed draw block operative when rotated to draw wire thereonto and form such wire into a coiled bundle which moves upwardly along said block as it grows, of driving means for said block, and spaced apart standards respectively carrying light source and light sensitive target elements with a light beam from the former element shining on the latter element and lying on a line tangent to a circle about said block and above such bundle so as to be cut off from said target element upon predetermined upward movement of such bundle, said driving means and target element being so connected together that the former is rendered operative and inoperative in response to such light beam shining on and being cut off from the latter respectively, one of said standards having a vertical lower portion and a horizontal upper portion extending generally toward said block and away from the other standard and carrying one of said elements at its free end.

6. In wire bundling mechanism, the combination with a vertically disposed draw block operative when rotated to draw wire thereonto and form such wire into a coiled bundle which moves upwardly along said block as it grows, of driving means for said block, spaced apart light source and light sensitive target elements with a light beam from the former element shining on the latter element and lying on a line tangent to a circle about said block and above such bundle, said driving means and target element being so connected together that the former is rendered operative and inoperative in response to such light beam shining on and being cut off from the latter respectively, and means on said block engaging the top of the bundle and forced upwardly during growth thereof and operative upon predetermined upward movement of such bundle to cut off such light beam from said target element, said elements being located radially outward of such bundle and said means to enable unobstructed lifting of such bundle and said means from said block.

7. In wire bundling mechanism, the combination with a vertically disposed draw block operative when rotated to draw wire thereonto and

5 form such wire into a coiled bundle which moves upwardly along said block as it grows, of driving means for said block, and spaced apart light source and light sensitive target elements with a light beam from the former element shining on the latter element and lying on a line tangent to a circle about said block and above such bundle so as to be cut off from said target element upon predetermined upward movement of such bundle, said driving means and target element being so connected together that the former is rendered operative and inoperative in response to such light beam shining on and being cut off from the latter respectively, said elements being located radially outward of such bundle to enable unobstructed lifting of the latter from said block.

20 8. In wire bundling mechanism, the combination with a vertically disposed draw block operative when rotated to draw wire thereonto and form such wire into a coiled bundle which moves upwardly along said block as it grows, of an electric drive motor for said block, a control circuit for said drive motor including a switch device for energizing and deenergizing said drive motor, said switch device comprising a light sensitive target element respectively opening and closing said control circuit upon a light beam shining thereon and being cut off therefrom, and a light source element spaced from said target element and projecting a light beam which shines on said target element and lies on a line tangent to a circle about said block and above in the path of upward growth of the bundle whereby upon predetermined growth of the bundle upwardly along said block such light beam is cut off from said target element to render said control circuit effective to deenergize said drive motor, said elements being located radially outward of such bundle to enable unobstructed lifting of the latter from said block.
